To all whom it may concern:

Be it known that I Marvin Camras (full name), a citizen of the United States and a resident of the city of Chicago, in the county of Cook and State of Illinois, have invented a new, original, and ornamental Design for a Magnetic Record Magazine or Similar Article, of which the following is a specification, reference being had to the accompanying drawing, forming a part thereof.

On the drawing:

Figure 3 is a fragmentary section taken on line III—III of Figure 2.

The back and the right side of the magazine are substantially plain.

The dominant features of the design reside in the portion shown in full lines.
